UNITED STATES PATENT OFFICE.

HENRY BENNING, OF CHICAGO, ILLINOIS.

ATTACHMENT FOR BABY-CARRIAGES.

No. 874,656.

Specification of Letters Patent.

Patented Dec. 24, 1907.

Application filed September 9, 1907. Serial No. 392,055.

To all whom it may concern:

Be it known that I, HENRY BENNING, citizen of the United States, residing at Chicago, in the county of Cook and State of Illinois, have invented certain new and useful Improvements in Attachments for Baby-Carriages, of which the following is a specification.

This invention is an attachment for baby carriages, and designed to enable a person to jog or bounce the same by the foot, thus allowing the hands of the attendant to be free for other work.

It comprises a bracket which may be readily attached to or detached from the carriage, and a foot piece supported by the bracket and adjustable to suit the height or length of the carriage and the position of the attendant.

20 The invention is illustrated in the accompanying drawings, in which,

Figure 1 is a side view of a carriage provided with the device. Fig. 2 is a side view of the attachment removed from the carriage. Fig. 3 is a rear view.

The device includes a supporting bar A which is adapted to extend across under the bottom of the carriage. This bar is preferably made of iron, and is upset at the ends 30 to form a clamp, in connection with the thumb screw B, whereby the bar may be clamped to the edges of the bottom of the carriage.

D indicate pieces of felt to prevent mar- 35 ring the carriage.

At the middle the supporting bar has a strap E which receives a rearwardly extending bar F. This bar is slideable in and out under the strap E, and may be fixed at adjustment by the thumb screw N. To the rear end of the bar F is connected a vertical bar G extending downward therefrom. A hinge K forms a suitable and cheap connection. A foot piece J is attached to the lower end of the piece G, by means of a bolt and thumb nut I which extends through a slot H in the vertical piece, thereby allowing the foot to be raised or lowered to the height de-

sired, or to suit the height of different carriages. A brace L extends between the bars F and G, being fixed to the bar F by a bolt and resting at its lower end against the cleat M secured to the bar G. This brace holds the parts in angular position while in use. But when the attachment is removed from the carriage it may be straightened to more convenient shape or position for storage, by turning the parts on the hinge K.

The attachment is clamped to the rear part of the bottom of the carriage, with the arm F extending rearwardly, and the piece G and foot J depending to convenient position to receive the pressure of the foot of the attendant who may either stand or sit behind or beside the carriage and jog or bounce the same as necessary or desirable. It will of course be understood that the carriage is provided with springs which yieldingly support the body and so allow the action referred to. When not desired for use, the attachment can be quickly removed by loosening the thumb screw B; or it may be pushed in out of the way and allowed to remain on the carriage, by loosening the thumb screw N and pushing the rod F forwardly.

I claim:

1. The combination with a carriage having a spring-supported body, of an attachment comprising a clamp secured to the bottom of the body, and a depending bar and foot piece supported by the clamp.

2. The combination with a spring-supported carriage body, of an attachment comprising a clamp bar extending across under the bottom of said body and secured thereto, a rearwardly extending arm fastened to the clamp bar, and a downwardly extending bar fastened to the rear end of said arm and provided with a foot piece.

In testimony whereof I affix my signature, 90 in presence of two witnesses.

HENRY BENNING.
